UNITED STATES PATENT OFFICE.

CHARLES A. RUSCO, OF CHICAGO, ILLINOIS.

STOVE OR FURNACE.

No. 831,243.

Specification of Letters Patent.

Patented Sept. 18, 1906.

Application filed December 27, 1904. Serial No. 238,497.

To all whom it may concern:

Be it known that I, CHARLES A. RUSCO, a citizen of the United States, residing at Chicago, in the county of Cook and State of Illinois, have invented new and useful Improvements in Stoves or Furnaces, of which the following is a specification, reference being made to the accompanying drawings, forming a part thereof.

10 This invention consists in an improvement adapted for stoves, furnaces, or other like objects.

It has the purpose of improving the combustion and giving more perfect control over 15 the fire.

It consists of the features of construction set out in the claims.

In the drawings, Figure 1 is a fore-and-aft vertical section through the fire-pot and ash-pit of a stove embodying this invention. Fig. 2 is a section at the line 2-2 on Fig. 1. Fig. 3 is a section at the line 3-3 on Fig. 1. Fig. 4 is a detail section at the line 4-4 on Fig. 1. Fig. 5 is a detail section at the line 5-5 on Fig. 2.

15 This improved stove comprises the customary principal elements, consisting of a base 1, containing the ash-pit, the fire-pot 2, mounted on the base, and suitable upper elements not concerned in the present invention. The fire-pot 2 has in its wall cells 3 3 extending up and down and circumferentially distributed throughout the said fire-pot wall. These cells communicate with the fuel or fire space of the fire-pot through rifts 3^a, which extend substantially the whole 35 length of the cells from top to bottom of the fire-pot, excepting a short distance at the top, having another purpose hereinafter explained. These cells open at their lower 40 ends at the bottom of the fire-pot freely and without restriction into an annular chamber encompassing the bottom of the fire-pot, which is preferably formed partly in the lower edge or end of the fire-pot and partly in the upper surface of the base—that is, on the 45 upper side of the upper wall of the ash-pit—and for the purpose of so forming this chamber the fire-pot has a flaring annular flange 4, forming under it an annular cavity 4^a, into the upper side of which all the cells 3 open freely, as stated, and the base has in the upper surface an annular pocket 5 corresponding to and registering with and making the annular cavity 4 of the fire-pot, so that said 55 annular cavity and said annular pocket together make up the annular chamber desired,

into which all the cells 3 open at their lower ends. At any convenient point, preferably at the rear of the stove or furnace, there is formed in the upper wall or upon the upper 60 side of the base an air-duct 6, of any desired width or circumferential extent, leading into the pocket 5, said air-duct being open and preferably grated at the outer end for free admission of outer air, which thus reaches the 65 annular chamber formed in the pocket 5 and cavity 4, and this annular chamber serves to distribute the air thus derived to the cells 3, through which the air reaches the fire-pot and may be delivered to the fire through the 70 rifts 3^a at any point in their height, either against the fire-body or over the fire, according to the depth of the latter in the fire-pot. A small amount of ash is liable to fall through the rifts 3^a into the cells 3 and be discharged 75 at the bottom into the annular air-distributing chamber described, and in order that such ash may not accumulate in this chamber so as to block up or materially obstruct the same to the extent of cutting off or 80 unduly restricting the air circulation therethrough the bottom of the pocket 5 is constructed so as to permit the discharge of the ashes therefrom periodically, as may be required. A convenient method of accomplishing this is to make the bottom of the 85 pocket grated or reticulated and to apply underneath the same a correspondingly-reticulated register-annulus 7, which may be oscillated a distance equal to the width of the ap- 90 ertures, so as to either close all the apertures or open them all in a familiar manner. In order to most efficiently accomplish the purpose of discharging the ashes by this means, the grate-bars 5^b of the grated bottom of the 95 pocket 5 are triangular in cross-section, as seen in Fig. 3, with the apex upward and the flat side downward against the register-annulus 7, so that the bottom of the pocket has substantially no extent of horizontal surface 100 upon which the ashes may lodge, the bars 7^a of the annular register-plate 7 being substantially the only support for the ashes, which are therefore immediately dropped when the register is moved to pass these bars under the 105 triangular grate-bars 5^b.

Since it is desired that the air for circulation through the annular chamber and to the cells 3 shall be derived from the exterior, and that the communication of the cells with the ash-pit shall be closed during the ordinary operation of the stove, I provide that the annular

register shall be normally in closed position and shall automatically return to that position after being moved for dropping the ashes out of the annular chamber as soon as the operator releases it. For this purpose the handle 8 of the annular register which extends out through a suitable slot 9 in the base has secured to one side of it a flat spring 10, whose free end bears against one end of the slot so that the spring elastically resists the movement of the handle toward that end and reacts to return it to the opposite end, the position at which the handle is thus normally held by the spring being the closed position of the register.

The ash-pit 12 in the base 1 has the customary opening at the front for removing the ashes which pass through the grate 13, which is, in part, the bottom of the fire-pot. This grate is preferably constructed and arranged so that it can be completely closed, and for this purpose it comprises radial fingers 13^a, which alternate with radial apertures, and the base has at the top inwardly-projecting radial fingers 1^b, alternating with corresponding intervals and of width corresponding both to the fingers and to the apertures of the grate, so that the grate being adapted to be oscillated about its vertical axis may at one position have its radial apertures completely closed by the fingers 1^b of the base and at another position may have its fingers registering over the fingers of the base and its apertures registering with the apertures between the base-fingers. The center of the grate is closed by a plate 14, which is provided with slide-bearings 14^a on the grate and is adapted to be drawn forward so as to open the center of the grate to permit the removal of clinkers or other matter too large to pass through the grate-apertures. The handle 14^b of the plate 14 serves as a handle for oscillating the grate to open and close it as described. The ash-pit entrance is closed, as usual, by a door 18, which is provided with draft-apertures and a register of familiar construction for regulating or completely cutting off, as may be desired, the access of air into the ash-pit, and thence through the grate to the fire; but for shutting off the air from the bottom of the fire the preferable method is to close the grate in the manner above explained. When the grate is thus closed, all the draft for the fire will be derived through the air-duct 6 and the annular chamber to which it leads and which supplies the cells 3, and after the fire is started this is designed to be the sole source of draft—that is, the grate or the ash-pit draft-register, either or both, will be closed, so that no air will enter the fire through the grate.

In order to obtain a certain advantage of additional air-supply at the top of the fire as distinguished from the air-supply which may pass through the rifts 3^a against the fire-body,

and into the body of coals, such additional air-supply being desirable for the purpose of effecting complete combustion of the gases arising from the coals for which adequate air-supply will not pass through the coals without unduly stimulating the fire, and thereby increasing the generation of gas, I provide around the top of the fire-pot an annular chamber 15, into which the upper ends of the cells 3 open freely, this chamber being above the level at which the rifts 3^a terminate. Preferably the chamber is formed in the casting of the fire-pot except as to an outer inclosing-wall, which is conveniently made of a separate plate 15^a, secured to the main fire-pot casting in any convenient manner. This annular chamber 15 is supplied with air from the exterior through a register 16 in the outer wall or plate 15^a, and the air is distributed by means of the annular chamber completely around the top of the fire-pot and it is delivered into the fire-pot above the fire therein through a multiplicity of small apertures 17 circumferentially distributed about the top of the fire-pot leading from said annular chamber 15. The result of this construction is that the air rising through the cells 3 and being highly heated in its passage, constituting a supply largely in excess of the discharge which will ordinarily take place through the rifts 3^a, fills the annular chamber 15 and being at that point further heated, together with the additional supply entering from outside through the register 16, is discharged forcibly in jets through the apertures 17 into the volume of gas in the fire-pot above the fire-body, and thus supplying the proper quantity of oxygen to the combustible gases produces combustion thereof, which causes the air-jets to assume the appearance of flame-jets. A sufficient number of discharge-apertures 17 being provided to correspond with the volume of fire which the fire-pot may contain will cause the combustion of the gases above the fire-body to be substantially perfect and prevent or greatly reduce the visible smoke discharged from the stove.

I claim—

1. In a stove or furnace, the combination of a fire-pot and base, the fire-pot having circumferentially-distributed air-cells extending up and down in its wall and communicating with the fuel-space, the base containing the ash-pit, and an annular chamber being formed at the junction of the fire-pot and base with which the air-cells of the fire-pot communicate at their lower ends, means normally closing air communication of said annular chamber with the ash-pit, and means for operating said closing means to open such communication at will, said chamber having draft communication with the outer air.

2. In a stove or furnace, the combination of a fire-pot and base, the fire-pot having circumferentially-distributed air-cells extend-

- ing up and down in its wall and communicating with the fuel-space, the base having an annular pocket in its top wall, said pocket communicating freely with the lower ends of said fire-pot cells; means normally closing air communication of the pocket with the ash-pit; means for operating said closing means to open such communication at will, and a draft-passage from the outer air leading into such pocket.
3. In a stove or furnace, the combination of a fire-pot and a base, the fire-pot having circumferentially-distributed air-cells extending up and down in its wall and communicating with its fuel-space, the base containing the ash-pit, and an annular chamber being formed at the junction of the fire-pot and base with which the air-cells of the fire-pot communicate at their lower ends, said annular chamber having at the bottom a movable closure cutting off communication of said chamber with the ash-pit and means for moving such closure at will to open passage for ashes from the chamber into the ash-pit.
- 15 4. In a stove or furnace, the combination of a fire-pot and a base, the fire-pot having circumferentially-distributed air-cells extending up and down in its wall and communicating with its fuel-space, the base containing the ash-pit, and an annular chamber being formed at the junction of the fire-pot and base with which the air-cells of the fire-pot communicate at their lower ends, said annular chamber having at the bottom a movable closure cutting off communication of said chamber with the ash-pit; means holding such closure normally closed, and means for moving such closure at will to open passage for ashes from the chamber into the ash-pit.
- 25 5. In a stove or furnace, in combination with a fire-pot and base, the fire-pot having circumferentially-distributed air-cells extending up and down in its wall, the base containing the ash-pit, and an annular chamber being formed at the junction of the fire-pot and base with which the air-cells of the fire-pot communicate at their lower ends, said annular chamber having draft communication with the outer air, and means normally closing air communication of said chamber with the ash-pit, the fire-pot having an annular chamber at the top into which the air-
- cells open freely at their upper ends, and a multiplicity of apertures circumferentially distributed about the fire-pot leading from 55 said annular chamber into the fire-pot cavity at the upper end, and a controlled draft-inlet into said upper annular chamber.
6. In a stove or furnace, the combination of a fire-pot and a base, the fire-pot having 60 circumferentially-distributed air-cells extending up and down in its wall and communicating with the fuel-space substantially throughout their vertical extent, the base containing an ash-pit, and an annular chamber being formed at the junction of the fire-pot and base with which said air-cells communicate at their lower ends, said annular chamber having draft communication with the outer air, and means normally closing air 65 communication of said chamber with the ash-pit, the fire-pot having also an annular chamber at the upper end into the lower side of which said fire-pot cells open freely at their upper ends, said annular chamber having 70 communication with the fire-pot cavity at the upper part of the latter by means of a multiplicity of apertures in the fire-pot wall circumferentially distributed about the fire-pot, said upper annular chamber having controlled draft communication with the outer 75 air.
7. In a stove or furnace, the combination of a fire-pot and base, the fire-pot having circumferentially-distributed air-cells extending 80 up and down in its wall and communicating with the fuel-space; the base containing the ash-pit, and an annular chamber being formed at the junction of the fire-pot and base with which the air-cells of the fire-pot 85 communicate at their lower ends, said annular chamber having draft communication with the outer air, and means for opening and closing communication of said chamber with the ash-pit at will.
8. In testimony whereof I have hereunto set my hand, in the presence of two witnesses, at Chicago, Illinois, this 16th day of December, 1904.

CHARLES A. RUSCO.

In presence of—

CHAS. S. BURTON,
FREDK. G. FISCHER.
